Attorney, Agent, or Firm—Polster, Lieder, Woodruff & Lucchesi**[57] CLAIM**

The ornamental design for a finger ring shank, as shown and described.

DESCRIPTION

FIG. 1 is a perspective view of a finger ring shank showing my new design with the top of the ring indicated in broken lines, but not forming part of the design;

FIG. 2 is a perspective view similar to FIG. 1, but showing insertion and removal of a diamond in the base of the shank;
FIG. 3 is a front elevational view;
FIG. 4 is a rear elevational view;
FIG. 5 is a left side elevational view;
FIG. 6 is a right side elevational view;
FIG. 7 is a top plan view; and,
FIG. 8 is a bottom plan view.*Primary Examiner*—Ralf Seifert**1 Claim, 1 Drawing Sheet**FIG. 1
